US00D979062S

(12) **United States Design Patent** (10) Patent No.: **US D979,062 S**
(45) Date of Patent: **** Feb. 21, 2023**

(54) **INTERBODY BONE IMPLANT**

- (71) Applicant: **Spinal Elements, Inc.**, Carlsbad, CA (US)
(72) Inventors: **Jason Blain**, Encinitas, CA (US); **Gregory Martin**, Encinitas, CA (US)
(73) Assignee: **Spinal Elements, Inc.**, Carlsbad, CA (US)
(**) Term: **15 Years**
(21) Appl. No.: **29/840,859**
(22) Filed: **Jun. 1, 2022**
